MOTOR CONSTRUCTION

Roy E. Deeble, Long Beach, Calif.

Application October 22, 1930. Serial No. 490,432

14 Claims. (Cl. 123—63)

This invention relates to engine or motor construction in which by a novel combination and arrangement of elements a desirable lightweight motor is produced.

5 In general the present invention relates to improvements in construction in reciprocating engines in which a movable piston provided with a skirt and with a longitudinal opening in the skirt is employed. More particularly it may be 10 said that the present invention relates to improvements on internal combustion engines of the character disclosed in Patent No. 1,832,282, issued November 17th, 1931.

The motors coming within the scope of this 15 invention include generally a cylinder containing a movable piston with expansion chambers on both sides of the piston head so that in effect two expansion chambers are formed in each cylinder.

20 By placing a valve assembly in operative communication with the space between a stationary bulkhead positioned in the skirt of the piston and the head of the piston and another valve assembly in operative communication with the 25 head of the cylinder, the motor may be used as a double acting internal combustion or reciprocating engine.

Motors including a cylinder, a piston and a stationary bulkhead within the cylinder and 30 piston skirt are rather difficultly assembled. The present invention is primarily directed to a mode of construction by means of which it is possible to assemble the motor readily without the use of complicated joints.

35 An object of the invention is to disclose and provide a reciprocating engine of the double acting type which is of simple lightweight construction.

Another object of the invention is to disclose 40 and provide a reciprocating engine including a cylinder, piston and a stationary bulkhead within the piston skirt, the construction being such as to permit ready assembly or dismantling for repairs.

45 A still further object is to disclose and provide an internal combustion engine of the double acting type which is light in weight and simple in construction.

A still further object is to disclose and provide 50 a reciprocating engine including a cylinder and piston skirt, the head of the piston being on one side of the bulkhead whereas the wrist pin assembly is on the other side of the bulkhead.

Other objects, uses and advantages of this 55 invention will become apparent to those skilled

in the art from the following detailed description of a preferred form of the invention, reference being had to the appended drawings in which, for illustrative purposes, a double acting four stroke cycle internal combustion engine is 60 shown. It is to be understood, however, that the invention is not limited to this adaptation and use on four stroke double acting internal combustion engines but may be applied to other forms of reciprocating engines and to their uses. 65

In the drawings:

Fig. 1 is a longitudinal section through one cylinder of a reciprocating engine embodying the construction of this invention.

Fig. 2 is a vertical section through the cylinder 70 shown in Fig. 1, said section being taken through the plane 2—2 indicated in Fig. 1.

Fig. 3 is an end view of the cylinder shown in Fig. 1.

Fig. 4 is a transverse section taken along the 75 plane 4—4 in Fig. 2.

The double acting engine shown in the drawings is of a type which is particularly adapted for use in automobiles, airplanes, motorboats and the like. 80

It is to be understood that the construction shown in the drawings is not only applicable to internal combustion engines of the type specifically described but may also be employed in the construction and assembly of various other 85 types of reciprocating engines, such as, for example, Diesel engines, compressors, pumps and various other types of reciprocating engines.

The engine may comprise one or more cylinders, each of said cylinders being preferably 90 made of sections such as the sections 1 and 2, suitably connected to each other as shown. The sections 1 and 2 come into abutting relation as indicated at 3 and a valve assembly ring 4 fits between the main portions of the sections 1 and 2, the valve assembly ring 4 including a valve chamber indicated at 5 containing inlet and outlet valve ports 6 and suitable valves 7. The cylinder sections 1 and 2 as well as the valve ring 4 are held together as by means of bolts 95 8 disposed with their axes substantially paralleling the axes of the cylinder sections.

One of the cylinder sections, as for example the upper cylinder section 1, may be provided with a head 9, the cylinder section 1 being in 100 operative communication with a valve assembly which, as shown in Fig. 1, is made a part of the head 9. The head 9 may be connected to the cylinder section 1 as by means of machine screws 10. Between the various joints, as be- 110

tween the cylinder section 1 and the head 9, or between the cylinder section 1 and the valve ring 4, suitable gaskets indicated at 11 may be employed.

5 The cylinders, valve rings and valve assemblies, shown in the drawings, are ribbed to provide large cooling areas. Furthermore, it is to be noted that in order to facilitate valve removal, ports are formed in the valve ring 4 above the valve seats 12 positioned in the valve chamber 5 and a bushing 13 threadedly mounted in such port. The bushing 13 may be internally threaded to receive a plug 14 having a central internally threaded bore indicated at 15 to receive a spark plug. The plug 14 may also be provided with ribs such as are indicated at 16 to facilitate cooling.

20 Slidably mounted within the cylinder composed of sections 1 and 2, for example, is a piston provided with a head 17 and a skirt 18 having a longitudinal slot therein, one edge of which is indicated at 19. The piston may carry suitable bearings for a wrist pin. The head 17 of the piston may be hollow and filled with a suitable heat absorbing medium, such as fluxing heat absorbing means. Sodium and lithium nitrate has been found effective for this purpose.

25 As shown, the piston skirt 18 may carry at its lower end wrist pin bosses 20. The longitudinal slot in the piston skirt 18 preferably extends from a point closely adjoining the head 17 to a point adjacent the open end of the piston skirt so as to leave a solid circular ring or piston skirt at the open end of the skirt and thus give strength to the piston as a whole.

30 Positioned within the cylinder and within the piston skirt 18 there is a stationary substantially transverse bulkhead generally indicated at 21. Said bulkhead is preferably composed of substantially circular sections adapted to be inserted into the skirt 18 through the longitudinal aperture 19. For example, the bulkhead 21 may consist of a member 22 of slightly smaller diameter than the internal diameter of the piston skirt 18. It is to be noted that the upper surface of the member 22 is slightly convex and that the lower edges of the member 22 are in the form of steps, thus providing a circular recess 23 and a deeper recess 24 adjoining the lower surface of the member 22. One or more of the recesses 23 may be used and two are shown in the member 22. These recesses 23 are adapted to receive externally expanding rings 25.

35 The bulkhead also includes a lower member 26 provided with a recess 27 complementary to the recess 24 formed in the member 22 and an adjoining recess 28 for another externally expanding sealing ring similar to the rings 25.

40 Each of the members 22 and 26 together with their sealing rings may thus be separately inserted into the piston 18 through the longitudinal aperture 19 and then by turning the members 22 and 26 they may be caused to assume a position substantially transverse to the longitudinal axis of the cylinder and of the piston skirt 18.

45 A key ring 44 fits into the complementary recesses 24 and 27, assures proper contact between the members 22 and 26 and as the line of contact between members 22 and 26 is approximately midway of the key ring 44, a gas-tight joint is assured.

50 The bulkhead 21 composed of the members 22 and 26 is then maintained in position within the piston and within the cylinder by means of

55 members 30 and 31 attached to the lower or open end of the cylinder and maintained in spaced relation with the interior surfaces of the cylinder.

60 As shown, the open end of the cylinder section 2 is provided with an inwardly extending lip 32 having ears 33 formed therein, (Fig. 3). The members 30 and 31 are also preferably formed with lugs 34 which are provided with internally threaded bores adapted to receive machine screws 35 extending through the ears 33 formed in the lip 32 into the lugs 34. In this manner, the members 30 and 31 are firmly attached to the lower end of the cylinder.

65 The bulkhead members 22 and 26 are also preferably provided with lugs 36. The upper ends of the members 30 and 31 are provided with similar ears 37 and the members 22 and 26 may thus be connected to the members 30 and 31 as by means of machine screws 38 extending into internally threaded bores formed in the lugs 36.

70 The member 30 may be provided with an externally extending portion 40 adapted to contact with the interior wall of the cylinder through the longitudinal aperture 19 formed in the piston skirt 18. A machine screw 41 may extend through the wall of the cylinder into the portion 40 and by means of such machine screw 41, the upper ends of the members 30 and 31 as well as the bulkhead 21 may thus be held in position against lateral movement.

75 A certain amount of space is left between the inner surface of the cylinder, the outer surface of the stationary bulkhead 21 and the edges of the longitudinal port 19 of the skirt 18. Means

76 have been provided for preventing leakage of gases from this opening and such means may comprise a segmental expandable shoe carried by the stationary bulkhead 21. Such an expandable shoe is indicated at 42 but need not be described in detail here as it is described in detail in the aforementioned co-pending application. The key ring 44 is of channel section and is adapted to receive a fin of said expandable shoe 42 and thus prevent vertical motion of the shoe 42. An expanding ring 39 is also carried by the key ring 44, said ring 39 being connected to sliding portions of the shoe 42 to maintain the same in contact with the longitudinal edges of the port 19.

80 The walls of the cylinder opposite the stationary bulkhead 21 may be provided with a plurality of annular grooves such as the grooves 43, each of said grooves being provided with an internally contracting sealing ring. The skirt of the piston 18 is thus held firmly between the externally expanding rings 25 carried by the bulkhead 21 and the contracting rings 43 carried by the cylinder wall.

85 It will thus be seen that means have been provided whereby a stationary bulkhead may be positioned within the piston skirt without the necessity of either removing the head of the piston or the wrist pin assembly. In assembling

86 the motor, the bulkhead members 22 and 26 and key ring 44 are separately inserted through the longitudinal aperture 19 into the piston skirt 18 and snapped together around the key ring 44.

90 The bulkhead is then fastened together and to the leg members 30 and 31 by means of the bolts 33. The piston, together with its bulkhead and leg members 30 and 31, is then inserted into the lower cylinder section 2 and the bulkhead

fastened into position by connecting the members 30 and 31 to the lugs 33 of the cylinder 2 by means of the machine screws 35.

Before legs 30 and 31 are firmly connected to the cylinder section 2 by the screws 35, the piston is partially revolved upon its own axis within the cylinder section 2 so as to align the bosses 20 with apertures 50 made in the lower portion of the cylinder section 2.

10 Wrist pins can then be inserted through the apertures 50 into the bosses 20 and connecting rod thus attached to the piston while the piston is in the cylinder section 2. After the wrist pins have been inserted, the piston is again partially rotated into normal position so that the cylinder walls prevent the wrist pin from coming out.

15 In effect, therefore, the piston is over one-half and approximately two-thirds the length of the entire cylinder, the head of the piston being adapted to move between the upper and lower valve assemblies which are in operative communication with the cylinder. The wrist pin assembly is positioned beneath the stationary bulkhead whereas the head of the piston is positioned above the bulkhead.

20 It is to be understood that the invention is not limited in its application to a cylinder made of sections or to a cylinder provided with a removable head such as the head 9. Instead it is quite evident that the invention may also be applied to cylinders provided with a removable head only. Furthermore, although the stationary bulkhead shown in the drawings is formed of two sections 22 and 26 and a key ring 44, it is to be understood that bulkheads may be made of one or more sections. Furthermore, although the piston head 17 is shown hollow, the invention is not limited thereto. Although the 25 construction shown illustrates an air cooled type of motor, it is obvious that similar constructions may be applied to a liquid cooled motor.

30 The advantages of the construction will be some obvious to those skilled in the art from a contemplation of the preferred form described hereinabove. Furthermore, numerous changes and modifications will become apparent to those skilled in the art and the invention embraces all such changes and modifications as come within the scope of the appended claims, the specific form of the invention described being merely illustrative of the construction.

I claim:

35 1. In a reciprocating engine including a cylinder provided with an open end, a movable piston within said cylinder, said piston including a skirt, provided with a longitudinal opening therein and wrist pin bearings carried by said skirt; a stationary bulkhead positioned within said cylinder and piston skirt and between the head and wrist pin bearings thereof, said bulkhead comprising substantially circular members insertable into said skirt through said longitudinal opening therein and movable into transverse position within the skirt, and means in said cylinder in spaced relation to cylinder walls connecting said bulkhead with the open end of said cylinder.

40 2. In a reciprocating engine including a cylinder provided with an open end, a movable piston within said cylinder, said piston including a skirt, a longitudinal opening in said skirt and wrist pin bearings carried by said skirt; a stationary bulkhead positioned within said cylinder

45 and piston skirt and between the head and wrist pin bearings thereof, said bulkhead comprising substantially circular members insertable into said skirt through said longitudinal opening therein and movable into transverse position within the skirt, means in said cylinder in spaced relation to cylinder walls connecting said bulkhead with the open end of said cylinder, and means for positioning said bulkhead laterally in said skirt and said cylinder.

50 3. In a reciprocating engine the combination of a cylinder provided with a head and an open end, a movable piston within said cylinder, said piston including a head, a skirt, a longitudinal opening in said skirt, and wrist pin bearings carried by said skirt, a stationary bulkhead positioned within said cylinder and piston skirt and between the head and wrist pin bearings thereof, said bulkhead comprising substantially circular members insertable into said skirt through said longitudinal opening therein and movable into transverse position within the skirt, means in said cylinder in spaced relation to cylinder walls connecting said bulkhead with the open end of said cylinder, expansion sealing rings carried by 100 said bulkhead, and contraction sealing rings carried by said cylinder in a transverse plane passing through said bulkhead.

55 4. In a reciprocating engine the combination of a cylinder provided with a head and an open end, a movable piston within said cylinder, said piston including a head, a skirt, a longitudinal opening in said skirt, and wrist pin bearings carried by said skirt, a stationary bulkhead positioned within said cylinder and piston skirt and between the head and wrist pin bearings thereof, said bulkhead comprising substantially circular members insertable into said skirt through said longitudinal opening therein and movable into transverse position within the skirt, means in 105 said cylinder in spaced relation to cylinder walls connecting said bulkhead with the open end of said cylinder, expansion sealing rings carried by said bulkhead, contraction sealing rings carried by said cylinder in a transverse plane passing 110 through said bulkhead, and means for positioning said bulkhead laterally in said skirt and cylinder.

60 5. In a reciprocating engine the combination of a cylinder provided with a head and an open end, a movable piston within said cylinder, said piston including a head, a skirt, a longitudinal opening in said skirt, and wrist pin bearings carried by said skirt, a stationary bulkhead positioned within said cylinder and piston skirt and 115 between the head and wrist pin bearings thereof, said bulkhead comprising substantially circular members insertable into said skirt through said longitudinal opening therein and movable into transverse position within the skirt, means in 120 said cylinder in spaced relation to cylinder walls connecting said bulkhead with the open end of said cylinder, an expansible shoe mounted on said bulkhead and fitting into the longitudinal opening in said piston skirt, expansion sealing 125 rings carried by said bulkhead, and contraction sealing rings carried by said cylinder in a transverse opening passing through said bulkhead.

65 6. In a reciprocating engine the combination of a cylinder composed of two longitudinal sections connected to each other, said cylinder being provided with a head at one end, the other end being open, a movable piston within said cylinder, said piston including a head, a skirt, a wrist pin assembly carried by said skirt and a 130

longitudinal opening in said skirt, a stationary bulkhead positioned within said cylinder and piston skirt and between the head and wrist pin bearings of said skirt, said bulkhead comprising substantially circular members insertable into said skirt through said longitudinal opening therein, means in said cylinder in spaced relation to cylinder walls connecting said bulkhead with the open end of said cylinder to maintain said bulkhead in transverse position substantially at the point of connection of said cylinder sections, a valve assembly in operative communication with the head of said cylinder, and a second valve assembly in operative communication through said skirt opening with the space between the piston head and stationary bulkhead.

7. In a reciprocating engine the combination of a cylinder composed of two longitudinal sections connected to each other, said cylinder being provided with a head at one end, the other end being open, a movable piston within said cylinder, said piston including a head, a skirt, a wrist pin assembly carried by said skirt and a longitudinal opening in said skirt, a stationary bulkhead positioned within said cylinder and piston skirt between the head and wrist pin bearings of said skirt, said bulkhead comprising substantially circular members insertable into said skirt through said longitudinal opening therein, means in said cylinder in spaced relation to cylinder walls connecting said bulkhead with the open end of said cylinder to maintain said bulkhead in transverse position substantially at the point of connection of said cylinder sections, a valve assembly in operative communication with the head of said cylinder, a second valve assembly in operative communication through said skirt opening with the space between the piston head and stationary bulkhead, expansion sealing rings carried by said bulkhead, contraction sealing rings carried by said cylinder in a transverse plane passing through said bulkhead, and an expansible shoe carried by said bulkhead and fitting into the longitudinal opening in said movable piston.

8. In a reciprocating engine the combination of two cylinder sections, each of said sections being provided with an annularly stepped end, a valve assembly ring adapted to receive said stepped ends of said cylinder sections, means for connecting said cylinder sections and valve assembly ring together, a head carried by one end of the cylinder thus formed, a valve assembly in operative communication with the head of said cylinder, the opposite end of said cylinder being open, a movable piston within said cylinder, said piston including a head, a skirt, wrist pin bearings carried by said skirt and a longitudinal opening in said skirt, a stationary bulkhead positioned within said cylinder and piston skirt and between the head and wrist pin bearings of said skirt, said bulkhead comprising substantially circular members insertable into said skirt through said longitudinal opening therein, and means in said cylinder in spaced relation to cylinder walls connecting said bulkhead with the open end of said cylinder to maintain said bulkhead in transverse position within said skirt.

9. In a reciprocating engine the combination of two cylinder sections, each of said sections being provided with an annularly stepped end, a valve assembly ring adapted to receive said stepped ends of said cylinder sections, means for

connecting said cylinder sections and valve assembly ring together, a head carried by one end of the cylinder thus formed, a valve assembly in operative communication with the head of said cylinder, the opposite end of said cylinder being open, a movable piston within said cylinder, said piston including a head, a skirt, wrist pin bearings carried by said skirt and a longitudinal opening in said skirt, a stationary bulkhead positioned within said cylinder and piston skirt and between the head and wrist pin bearings of said skirt, said bulkhead comprising substantially circular members insertable into said skirt through said longitudinal opening therein, means in said cylinder in spaced relation to cylinder walls connecting said bulkhead with the open end of said cylinder to maintain said bulkhead in transverse position within said skirt, and means for positioning said bulkhead laterally in said skirt and cylinder.

10. In a reciprocating engine the combination of two cylinder sections, each of said sections being provided with an annularly stepped end, a valve assembly ring adapted to receive said stepped ends of said cylinder sections, means for connecting said cylinder sections and valve assembly ring together, a head carried by one end of the cylinder thus formed, a valve assembly in operative communication with the head of said cylinder, the opposite end of said cylinder being open, a movable piston within said cylinder, said piston including a head, a skirt, wrist pin bearings carried by said skirt and a longitudinal opening in said skirt, a stationary bulkhead positioned within said cylinder and piston skirt and between the head and wrist pin bearings of said skirt, said bulkhead comprising substantially circular members insertable into said skirt through said longitudinal opening therein, means in said cylinder in spaced relation to cylinder walls connecting said bulkhead with the open end of said cylinder to maintain said bulkhead in transverse position within said skirt, and means for positioning said bulkhead laterally in said skirt and cylinder.

11. In a reciprocating engine the combination of two cylinder sections each provided with a stepped end, a valve assembly ring adapted to receive the stepped ends of said cylinder sections, means for connecting said valve assembly and cylinder sections together, a port in the cylinder thus formed in operative communication with the valve assembly carried by said ring, a head carried by one end of the cylinder, a valve assembly in operative communication with the head of said cylinder, the opposite end of said cylinder being open, a movable piston within said cylinder, said piston including a head, a skirt, a wrist pin assembly carried by said skirt and a longitudinal opening in said skirt, the head of said piston being adapted to move between the head of said cylinder and said valve assembly ring, a stationary bulkhead positioned within said cylinder and piston skirt and between the head and wrist pin bearings of said skirt, said bulkhead comprising substantially circular members insertable into said skirt through said longitudinal opening therein and movable into transverse position within the skirt, means in said cylinder in spaced relation to cylinder walls connecting said bulkhead with

the open end of said cylinder, and means for positioning said bulkhead laterally in said skirt and cylinder.

12. In a reciprocating engine the combination of two cylinder sections each provided with a stepped end, a valve assembly ring adapted to receive the stepped ends of said cylinder sections, means for connecting said valve assembly and cylinder sections together, a port in the cylinder thus formed in operative communication with the valve assembly carried by said ring, a head carried by one end of the cylinder, a valve assembly in operative communication with the head of said cylinder, the opposite end of said cylinder being open, a movable piston within said cylinder, said piston including a head, a skirt, a wrist pin assembly carried by said skirt and a longitudinal opening in said skirt, the head of said piston being adapted to move between the head of said cylinder and said valve assembly ring, a stationary bulkhead positioned within said cylinder and piston skirt and between the head and wrist pin bearings of said skirt, said bulkhead comprising substantially circular members insertable into said skirt through said longitudinal opening therein and movable into transverse position within the skirt, means in said cylinder in spaced relation to cylinder walls connecting said bulkhead with the open end of said cylinder, means for positioning said bulkhead laterally in said skirt and cylinder, expansion sealing rings carried by said bulkhead, an expansible shoe packing carried by said bulkhead and fitting into the longitudi-

nal opening in said movable piston, contraction rings carried by said cylinder in a transverse plane passing through said bulkhead, and means for adjustably positioning said bulkhead laterally in said skirt and cylinder.

80

13. In a reciprocating engine the combination of a cylinder provided with a head and an open end, a movable piston within said cylinder, said piston including a hollow head, a skirt, a longitudinal opening in said skirt, and wrist pin bearings carried by said skirt, said hollow head being filled with a heat absorbing medium, a stationary bulkhead positioned within said cylinder and piston skirt and between the head and wrist pin bearings thereof, said bulkhead comprising substantially circular members insertable into said skirt through said longitudinal opening therein and movable into transverse position within the skirt, and means in said cylinder in spaced relation to cylinder walls connecting said bulkhead with the open end of said cylinder.

85

14. In a reciprocating engine including a piston provided with a longitudinal slot in the skirt thereof, the provision of a plurality of substantially circular members provided with complementary faces, said members being insertable into said skirt through said longitudinal opening and movable into transverse position within the skirt, and means for holding said members in transverse position with complementary faces together.
